United States Patent Office

Des. 208,275

Patented Aug. 8, 1967

208,275

EGG CARTON

David L. Pearl, 333 Peachtree Hills Ave., Atlanta, Ga. 30305; John G. Waller, Atlanta, Ga. (806 E. Cambridge Ave., College Park, Ga. 30022); and Beverly P. Head, Jr., 9 Rockdale Lane, Birmingham, Ala. 35213

Filed June 20, 1966, Ser. No. 2,741

Term of patent 14 years

(Cl. D58—13)

Fig. 1

Fig. 2

Fig. 3

Fig. 4

FIG. 1 is a front-top perspective view of an egg carton embodying our new design;

FIG. 2 is a rear-bottom perspective view of the egg carton shown in FIG. 1;

FIG. 3 is a perspective view showing the egg carton of FIG. 1 in open position; and

FIG. 4 is a front elevational view of the egg carton shown in FIG. 1 in open position.

We claim:

The ornamental design for an egg carton, substantially as shown.
